PIPE CUTTER

William F. Errig, Philadelphia, and George M. Pfundt, Churchville, Pa., assignors to Peco Manufacturing Corporation, Philadelphia, Pa., a corporation of Pennsylvania

Application June 4, 1934, Serial No. 728,976

2 Claims. (Cl. 81—187)

This invention relates to pipe cutters of the type adapted for easily severing thin walled pipes, rubber tubing or hose, and other articles not involving more than manual effort.

5 More specifically our invention has reference to cutter devices comprising a bracket adapted for rigid fixture and a cutter element supported thereby in inclined relation to said bracket, severance of tubing being effected by rotary movement thereof relative to the cutter element.

10 The primary object of our invention is to provide a tube cutter which is simple to construct, easy to operate, and cheap to manufacture.

15 Another object is the provision of cutter of the type above indicated which is accurate, clean and easy to operate, time and labor saving, as well as eliminating makeshift tools such as hack saws and the like.

20 With the foregoing and other objects in view as will hereinafter become apparent, or to which specific reference will be made, our novel pipe cutter essentially comprises a supporting component which may be rigidly secured to a vertical or horizontal stationary element, and a 25 cutter supported by the component aforesaid in alignment with an impressed indicator whereby accuracy of the cut at right angles to the axis of the pipe being severed is positively ensured.

25 In the accompanying sheet of drawing there is illustrated one practical embodiment of our invention, like characters of reference being applied to corresponding parts in all the views.

30 Fig. I is a perspective view of our improved pipe cutter as attached to a vertical structure, 35 and showing a portion of rubber hose in process of being severed.

Fig. II is a front elevation of the pipe cutter.

35 Fig. III is a vertical section on the line III—III in the preceding illustration, as viewed in the 40 direction of the arrows.

Fig. IV is a section on the line IV—IV in Fig. III also looking in the direction of the 45 arrows thereon; and

Fig. V is an elevational view of our improved 50 pipe cutter secured to a horizontal structure.

In the drawing we have shown a form of our device 1 preferably, although not essentially, adapted for cutting thin radiator tubing or rubber hose. As disclosed the device 1 consists of 55 a somewhat channel-shaped bracket, fashioned to provide a main portion 2 having one end relatively angled at 3, and pierced with holes 4, for passage of securing means, such as screws 5, whereby the device 1 is fixed to a vertical wall 6, 60 for example. The main portion 2 and angled

end 3 are reinforced by an outward embossment 7 extending longitudinally of said main portion and angled end for rigidity, while additional holes 8 are provided in the main portion 2, proximate angled end 3 whereby the device 1 can be rigidly attached to a horizontal structure, as conventionally indicated at 6 in Fig. V.

The other or outer end 9 of the main portion 2 is also angled, relative to said main portion, and it is medially stamped out to provide a cutter-supporting flange 10 in alignment to one side of a central, longitudinally-extending, impressed score or indicator-groove 11, in the main portion 2 and lower part of the reinforcing embossment 7, aforesaid.

15 The cutter 12 is fashioned, from suitable metal, with an angled penetrator point 13 and cutting edge 14 which, when said cutter is secured to the supporting flange 10 as by stove bolts 15 passed through registering holes in both 20 the cutter 12 and flange 10, are both in direct alignment with the indicator-groove 11, as best understood from Fig. II.

25 Since the end sections are disposed at angles greater than a right angle with respect to the main section, the end section bearing the blade will form at its juncture with the main section a seat for receiving the pipe to be cut.

30 In using the device to cut a piece of rubber hose as indicated at 16 in Fig. I, the operator places said hose, transversely across the main portion 2 of the device 1, and draws said hose 16 sharply forward against the penetrator point 13 of the cutter 12, whereupon the pipe or hose will ride down the main section and enter the 35 seat formed at the juncture of the main portion or section 2 and the end 9. This operation is followed by rotating the hose 16 clockwise or toward the cutting edge 14 of the cutter 12 and using the indicator-groove 11 as a guide.

40 From the foregoing, it will be obvious that we have provided a simple and efficient device whereby thin metal tubings and rubber hose, of different diameters, may be expeditiously cut into desired lengths with ease and a minimum 45 of manual effort.

Obviously minor changes may be made in the form of our device, and it is intended to include all such changes as may be reasonably included within the scope of the following claims and the prior art permits.

50 Having thus described our invention, we claim:—

55 1. A pipe cutter comprising a main section and end sections, the end sections being disposed

at angles greater than a right angle with respect to the main section, one of said end sections having a flange extending laterally thereof and an opening therein, a cutting blade carried by the flange and extending through the opening with its cutting edge overhanging the main section, and means for securing the other end section to a support.

2. A pipe cutter comprising a main section and end sections, the end sections being disposed

at angles greater than a right angle with respect to the main section, a cutting blade carried by one end section, means for attaching the other end section to a vertical support, the blade bearing end section forming in conjunction with the main section a seat adapted to receive a pipe when placed on the main section and said end section.

WILLIAM F. ERRIG.
